RATCHET DRIVE FOR TOOLS

George G. Shurtleff, Panama City, Fla.

Application August 3, 1946, Serial No. 688,364

10 Claims. (Cl. 74—127)

1

This invention relates to new and useful improvements and structural refinements in ratchet drives for tools, more specifically, to a ratchet drive such as may be conveniently and effectively employed as a socket screw driver or wrench.

The principal object of the invention is to provide a ratchet drive for such screw driver or wrench, which is of a flexible character, in order that the wrench socket may be conveniently employed in restricted or poorly accessible locations, where wrenches of conventional design could not be efficiently used.

A further object of the invention is to provide a ratchet drive which may be quickly and conveniently manipulated.

Another object of the invention is to provide a ratchet drive which will readily lend itself for use in various modified forms or stages of assembly, as will be hereinafter more fully set forth. In this manner, the versatility and the general utility of the invention is considerably enhanced.

An additional object of the invention is to provide a ratchet drive which is simple in construction and operation and which cannot easily become damaged.

A still further object of the invention is to provide a ratchet drive which will readily lend itself to economical manufacture.

With the above important objects in view, and such other objects as may become apparent as this specification proceeds, the invention consists essentially of the arrangement and construction of parts as illustrated in the accompanying drawings, in which—

Figure 1 is a side elevation of the invention.

Figure 2 is a longitudinal, cross-sectional view thereof.

Figure 3 is a side elevation of the same.

Figure 4 is an end view, taken in the direction of the arrow 4 in Figure 1.

Figure 5 is a cross-sectional view, taken in the plane of the line 5—5 in Figure 2.

Figure 6 is a cross-sectional view, taken in the plane of the line 6—6 in Figure 2.

Figure 7 is a further end view of the invention.

Figure 8 is a plan view of the ratchet drive mechanism and handle used in the invention, showing the same associated with a modified form of a socket receiving adaptor with respect to those illustrated in the preceding figures.

Figure 9 is a perspective view of the ratchet sleeve and hand grip.

Figure 10 is a perspective view of the socket receiving adaptor and stem, and

2

Figure 11 is a fragmentary view of the ratchet screw.

Like characters of reference are used to designate like parts in the specification and throughout the several views.

Referring now to the accompanying drawings in detail the invention embodies in its construction an elongated yoke designated generally by the reference character 15, the same being configurated substantially as shown and consisting of the side members 16 and the end members 17.

In effect, the yoke 15 constitutes a handle and it will be noted that the side members 16 thereof are provided with longitudinally extending bores 18, the purpose of which will be hereinafter more fully described.

A reversible ratchet screw 19 of conventional design is rotatably journaled in the end members 17 of the yoke 15, one of the end members 20 being provided with a suitable bore 20, while the remaining end member 17 is formed with a boss 21 formed with a bore 22, for the purpose of journaling the screw 19 in the yoke.

A ratchet sleeve 23 is slidably positioned on the screw 19, the sleeve being equipped with a clutch 24, this in turn, being adapted for co-action with the "thread" end of the screw 19. The screw together with the sleeve 23 and the catch 24 constitute a ratchet mechanism of conventional design, in which the sliding of the sleeve will effect a clockwise or an anti-clockwise rotation of the screw, depending upon the setting of the clutch 24. It is believed that the operation of this ratchet mechanism is well-known in the art, and accordingly, further description thereof at this point is deemed unnecessary.

The sleeve 23 is provided with a pair of arms, constituting a diametrically extending cross-head or hand-grip 25. The outer extremities 40 of this cross-head are formed with guide portions 26, these extending through longitudinal slots 27 provided in the side members 16 and slidably engaging the aforementioned bores 18. It will be noted that one end of each of these bores 45 is closed and a compression spring 28 is positioned between the closed end of each bore and the guide 26, for urging the cross-head 25 in the direction of the arrow 29. A suitable set screw 30 is provided in the remaining end of each of the bores 18, to limit the sliding movement of the cross-head.

A further boss 31 is formed on the remaining end member 17, this boss in turn, being formed with a counter-bore 32, to receive a coupling 33. 55 The adjacent end of the screw 19 projects into

the boss 32 and engages this coupling, the screw 19 being provided with a ball 34 on which the coupling may be "snapped" and retained in position thereby.

The outer lateral surface of the boss 31 is equipped with a spring pressed ball 35, this being adapted for co-action with a connector sleeve 36. This sleeve is configurated substantially as shown and it will be apparent that by virtue of the ball 35, the sleeve may be separably connected or "snapped on" to the boss 31.

A flexible conduit 37 is secured at one end thereof in the sleeve 36, and a flexible cable 38 is rotatably positioned in the conduit 37, as will be clearly apparent from the accompanying drawings. One end of the cable 38 is secured in an adaptor bushing 39, this bushing being adapted for separable connection to the aforementioned coupling 33, by means of the spring pressed ball 40.

It will be apparent that in the aforementioned manner, the conduit 37 together with the associated cable 38 may be readily disconnected from the boss 31 and the coupling 33 respectively.

It will be also observed that the bushing 39 is provided with a suitable groove to receive a horseshoe-shaped keeper 39', the latter engaging a seat, so to speak, formed at the inner end of a counterbore 36' provided in the aforementioned sleeve 36. The purpose of the keeper 39' will be hereinafter more fully explained.

The outer end of the cable 38 is secured in a shank 41, this projecting from the adjacent end of the conduit 38 and terminating in a fork 42. This fork is provided with a pair of transversely aligned apertures 43 adapted to receive a pivot pin 44, the latter also passing through a further aperture 45 provided in a tool receiving adaptor 46. In this manner, the adaptor 46 is pivotally connected to the fork 42 and a suitable spring pressed ball 47 is provided in the fork 42 for normally retaining the adaptor 46 in the longitudinally extended position.

The adaptor 46 is, of course, designed to receive suitable wrench or screw driver sockets (not shown), a suitable ball 48 being provided on the adaptor, for removably retaining said sockets in position thereon.

Referring again to the aforementioned screw 19, the same is removably retained in position in the yoke 15 by a horseshoe-shaped keeper 49, removably engaging an annular groove 50 formed adjacent the end of the screw 19. The keeper 49 is seated in a counterbore 51 formed in the end member 17, and a suitable set screw 52 is employed for retaining the entire assembly in position.

When the invention is placed in use, the wrench or screw driver socket is applied to the adaptor 46 as already described, and by holding the outer end member 17 of the handle 15 and simultaneously pressing the hand-grip 25 in the direction of said member as shown at 53, the sliding of the sleeve 23 on the screw 19 will effect a corresponding rotation of the socket. The direction in which the socket is rotated is, of course, dependent upon the setting of the clutch 24, and it will be apparent that in this manner, the socket may be rotated so as to tighten or loosen the bolt, or the like, to which it is applied.

By virtue of the inherent flexibility of the conduit 37 and the cable 38, the socket on the adaptor 46 may be operated at various angles with respect to the longitudinal axis of the screw

19. The advantages of this arrangement will be readily appreciated when the invention is used in restricted or poorly accessible locations.

It will be also noted that the springs 28 will assist in returning the hand-grip 25 to its original position adjacent the cable end of the yoke 15, thereby preparing the same for the next tightening or loosening operation.

It should be stated at this point that when the handle 15 is separated from the flexible cable 38 and the sleeve 36, as has been already explained, the cable 38 may be withdrawn from the conduit 37 for purposes of cleaning, inspection or repair. This is accomplished by simply sliding the free end of the cable 38 inwardly (in the direction of the arrow 4 in Figure 1), so as to expose the adaptor bushing 39 and the keeper 39' at the relatively opposite end of the conduit, namely, at the end of the conduit provided with the sleeve 36. The keeper 39' may then be removed from the adaptor bushing 39, whereupon the cable 38 may be withdrawn from the opposite end of the conduit.

Particular reference now being had to the accompanying Figure 8, the flexible cable 38, together with its conduit 37, may be removed from the handle 15, in the manner already described, and a solid stem 54 may be applied directly to the coupling 33, in place of the flexible cable. The stem 54 is provided at the outer end thereof with a socket receiving adaptor 55, and the operation of the invention when used in this manner, is similar to that already described, with the exception of the advantages afforded by the flexibility of the cable 37.

Referring again to the primary embodiment of the invention, it will be noted that the pivoted connection of the adaptor 46 to the fork 42 will permit the conduit 37 and the associated handle 15 to be angulated with respect to the adaptor and socket associated therewith. In this manner, the handle and conduit may be employed with increased mechanical advantage for the final tightening or the initial loosening of bolts, to which the invention is applied.

In addition to its use in association with wrench sockets as herein described, the invention may obviously also be used with other tools, such as screw drivers, drill chucks and the like.

It is believed that the advantages and use of the invention will be clearly understood from the foregoing disclosure and accordingly, further description thereof at this point is deemed unnecessary.

While in the foregoing there has been shown and described the preferred embodiment of this invention it is to be understood that minor changes in the details of construction, combination and arrangement of parts may be resorted to without departing from the spirit and scope of the invention as claimed.

What I claim as my invention:

1. A ratchet drive for tools comprising in combination, a yoke forming a handle, a ratchet screw rotatably journaled in said yoke, a slideable ratchet sleeve positioned on said screw and adapted for co-action therewith, a hand-grip on said sleeve, said hand-grip engaging the sides of said yoke, a flexible conduit separably connected at one end thereof to said yoke, a flexible cable rotatably positioned in said conduit and separably connected at one end thereof to said screw, and a tool receiving adaptor at the remaining end of said cable.
2. The device as defined in claim 1 together

with means for restricting the extent of sliding of said sleeve.

3. A ratchet drive for tools comprising in combination, an elongated yoke forming a handle, a reversible ratchet screw rotatably journaled in said yoke, a ratchet sleeve slidably positioned on said screw and adapted for co-action therewith, a hand-grip on said sleeve, said hand-grip slidably engaging the sides of said yoke, means for restricting the extent of sliding of said hand-grip and said associated sleeve, a flexible conduit separably connected at one end thereof to one end of said yoke, a flexible cable rotatably positioned in said conduit and separably connected at one end thereof to said screw, a shank at the remaining end of said cable, said shank projecting from said conduit and forming a fork at the projecting extremity thereof, and a tool receiving adaptor pivotally mounted in said fork, the sliding of said sleeve causing the rotation of said adaptor.

4. In a tool driving mechanism, an elongated yoke forming a handle, a ratchet screw rotatably journaled in said yoke, a slidably ratchet sleeve slidably positioned on said screw and adapted for coaction therewith, a hand grip provided on said sleeve and slidably engaging the sides of said yoke, and means for operatively connecting said screw to a tool.

5. The device as defined in claim 4 wherein said means includes a tool driving member and a coupling separably connecting said member to said screw.

6. The device as defined in claim 4 wherein said yoke provides a stop for said sleeve, and resilient means for urging said sleeve against said stop.

7. The device as defined in claim 4 together

with adjustable stops provided on said yoke to engage said hand grip, and resilient means for urging said hand grip against said stops.

8. In a tool driving mechanism, an elongated yoke having side and end portions and forming a handle, a ratchet screw rotatably journaled in said end portions, a coacting ratchet sleeve slidable on said screw, a transversely extending hand grip on said sleeve, the side portions of said yoke being formed with laterally slotted and longitudinally extending bores, the end portions of said hand grip terminating in guides slideable in said bores, adjustable stops and compression springs in said bores, said springs engaging said guides and urging the same toward said stops, and means for operatively connecting said screw to a tool.

9. The device as defined in claim 8 wherein said means includes a tool driving member and a coupling separably connecting said member to said screw.

10. The device as defined in claim 8 wherein portions of said bores are screw-threaded, said adjustable stops comprising externally rotatable set screws provided in the screw-threaded portions of said bores.
